Jack A. Chay

Attorney

UNITED STATES PATENT OFFICE.

UA LEWIS, OF DALLAS, TEXAS.

SELF-SERVING CONTAINER.

Application filed November 26, 1923. Serial No. 677,113.

To all whom it may concern:

Be it known that I, UA LEWIS, citizen of the United States of America, residing at Dallas, in the county of Dallas and State of Texas, have invented certain new and useful Improvements in Self-Serving Containers, of which the following is a specification.

This invention relates to new and useful improvements in self-serving containers. It is customary to use devices at drug stores, restaurants and the like, for dispensing matches, tooth picks, drinking straws, in limited quantities, but these devices require refilling when empty, involve an investment, are more or less complicated and are likely to get out of working order. At very busy or rush hours it is inconvenient to refill these devices and at other times it is likely to be forgotten. The foregoing is recited merely to point out the need for my invention and not with any intent to reflect upon the merit of these former devices.

The object of my invention is to provide an inexpensive container in which the matches, toothpicks, drinking straws and the like may be packed and sold to the customer in the usual manner of such vending, but arranged with dispensing means easily and quickly adjusted to dispense the contents in limited quantities.

A particular object is to install said dispensary or delivery means in the container with substantially no reduction in its capacity, whereby said containers may be made of the same general style and size as those now in common use.

A further object is to provide a delivery member which may also serve as a closure for retaining the commodity in the container during shipping and at other times.

A construction designed to carry out the invention will be hereinafter described together with other features of the invention.

The invention will be more readily understood from a reading of the following specification and by reference to the accompanying drawings, in which an example of the invention is shown, and wherein:

Fig. 1 is a longitudinal sectional view of a tooth pick box constructed in accordance with my invention,

Fig. 2 is an end elevation of the same,

Fig. 3 is a plan view of the dispensing partition,

Fig. 4 is a cross-section on the line 4—4 of Fig. 3.

Fig. 5 is a longitudinal section view of a match box constructed in accordance with my invention, and

Fig. 6 is an end elevation of the same.

In the drawings the numeral 10 designates the bottom of a tooth pick box which has upright sides 11 and a hinged top 12, provided with a flap 13 adapted to fold down inside on the front side 11. In forming the boxes, sections of the sides are folded at right angles to form ends 14 and sections of its bottom are folded up to provide covers 15 for the ends. These covers are provided with flaps 16 under-lying the cover. This is a construction in common use.

The essence of my invention is an inclined transverse partition extending longitudinally of the box, which preferably is formed of two sections 17 and 18, respectively. The partition extends from the intersection of the bottom 10 and one of the ends 14 to the intersection of the top 12 and the other end. Each partition section overlaps the inner end of the other section and has fingers 19 bent over the edges of the other section, whereby a sliding connection is had and the sections are prevented from sagging. Any form of adjustable partition may be employed.

Each end 14 is provided with a transverse slot 20 contiguous to the partition and has a central arched opening 21. The outer end of each partition section has its end bent upward to form a transverse trough 22 which normally is positioned in the slot 20 to form a closure over which the cover is folded for shipping.

The toothpicks are packed in the box above and below the partition, which owing to its thinness, takes little space and does not reduce the capacity to an appreciable extent.

When it is desired to dispense tooth picks one of the covers 15 is pulled outwardly and torn off as is indicated in Fig. 1. One of the partition sections is then pulled outwardly a short distance by grasping the trough 22. The box is rested on its bottom 10 and the tooth picks on top of the inclined partition will flow by gravity through the slot 20 and into the trough 22. The trough may have a central notch 23 co-acting with the arch 21 to accommodate

the finger and thumb in picking up the articles. The trough may be adjusted to govern the quantity of picks exposed.

When the tooth picks above the partition 5 are exhausted the trough is pushed inwardly into the slot 20 and the box inverted. The trough at the other end is pulled outward after the cover 15 has been removed. The picks in the box may thus be 10 served without opening the same. The box may be packed at the factory with the partition in place. The picks need not be handled until taken hold of by the user. When the box is empty it may be thrown 15 away as it will cost but little more than the boxes now in common use.

A device of this character permits of a wide use and may be used for vending or dispensing cigarettes, drinking straws, 20 pencils, matches and various other articles of a cylindrical or elongated shape, in fact any article that will slide or roll down an inclined partition, and which may be packed in a box. In Figs. 5 and 6 I have 25 shown as a further illustration, a match box.

The box comprises a shell having a bottom 30, upright sides 31 and a top 32, the ends being open. A tray comprising a bottom 33, sides 34 and ends 35 is slidable in 30 the shell. The lower portion of one end has a slot 36, while the upper edge of the other end has a similar slot 36. The partition 17 is placed in the box so that its 35 troughs 22 lie in slots 36 and form closures. When it is desired to vend the matches, one of the troughs is pulled out as is shown in Fig. 1.

Various changes in the size and shape 40 of the different parts as well as modifications and alterations may be made within the scope of the appended claims.

What I claim, is:

1. In a reversible self-serving container, 45 an inclined partition within the container, and serving troughs at each end of the partition, one of the troughs receiving articles from one side of the partition and the other trough receiving articles from the other 50 side of the partition when the container is inverted.

2. In a reversible self-serving container, a receptacle having openings at its opposite ends at different elevations, an inclined partition in the receptacle extending from one opening to the other, and serving troughs at the openings for receiving articles passing down the partition. 55

3. A dispensing partition for a self-serving package box, comprising longitudinally 60 aligned relatively adjustable sections having troughs at their outer ends on opposite sides of the partition.

4. In a self-serving container, a receptacle having openings at its ends, an inclined partition in the receptacle, troughs 65 at the ends of the partition forming closures for the openings and movable outwardly for delivering articles from the partition.

5. In a self-serving container, a receptacle having openings at its ends, and an inclined partition in the receptacle comprising adjustable sections having troughs 70 at their ends normally at the openings of the receptacle, said sections being adjustable relatively of said openings, whereby 75 said troughs may be pulled outwardly to deliver articles from the partition.

6. In a self serving container, a receptacle having an opening formed at one end, an inclined feeding member in the receptacle 80 supporting the articles to be dispensed through said opening, said member being longitudinally extensible through the opening of the receptacle and having a trough 85 on its extended end outside of the receptacle.

7. In a self serving container, a receptacle having an opening formed at one end, an inclined feeding member in the receptacle 90 supporting the articles to be dispensed through said opening, said member being longitudinally extensible through the opening of the receptacle and having a trough 95 on its extended end outside of the receptacle, said member being retractable whereby said trough forms a closure for the opening.

In testimony whereof I affix my signature.

UA LEWIS.
